US0D1065917S

(12) **United States Design Patent** (10) Patent No.: **US D1,065,917 S**
(45) Date of Patent: ** Mar. 11, 2025

(54) **FOOD PROCESSOR**

- (71) Applicant: **WHIRLPOOL CORPORATION**,
Benton Harbor, MI (US)
- (72) Inventors: **John W. McConnell**, St. Joseph, MI
(US); **Brandon Tyler Mock**, St. Joseph,
MI (US); **John Jay Myers**, Saugatuck,
MI (US); **Nicholas Hill Schutte**, St.
Joseph, MI (US); **Rex D. Wilson**,
Stevensville, MI (US)
- (73) Assignee: **WHIRLPOOL CORPORATION**,
Benton Harbor, MI (US)

(**) Term: **15 Years**

(21) Appl. No.: **29/853,755**

(22) Filed: **Sep. 19, 2022**

(51) LOC (15) Cl. **31-00**

(52) U.S. Cl.

(57)

CLAIM

The ornamental design for a food processor as shown and described.

DESCRIPTION

FIG. 1 is a top perspective view of a food processor according to the claimed design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom perspective view thereof.

The portions of the article shown in broken line form no part of the claimed design.

1 Claim, 8 Drawing Sheets
